US00D643732S

(12) **United States Design Patent**
Cummings et al.

(10) **Patent No.:** **US D643,732 S**
(45) **Date of Patent:** ** *Aug. 23, 2011

(54) **BOTTLE**

(75) Inventors: **Bruce Cummings**, New York, NY (US);
Simon Dutton, New City, NY (US);
Caroline Fontana, Puteaux (FR); **Isaac Milhem**, Jersey City, NJ (US); **Guilhem Rousselet**, Saint Maure des Fossés (FR); **Nick Verebelyi**, London (GB)

(73) Assignee: **Colgate-Palmolive Company**, New York, NY (US)

(**) Term: **14 Years**

(21) Appl. No.: **29/339,931**

(22) Filed: **Jul. 10, 2009**

(51) LOC (9) Cl. **09-01**

(52) U.S. Cl. **D9/543**; D9/563; D9/565; D9/569; D9/571; D9/575

(58) **Field of Classification Search** D9/516, D9/530, 538, 540-543, 550-552, 556-558, D9/563-565, 569-571, 575, 682, 685-686, D9/693; 215/381-385

See application file for complete search history.

Primary Examiner — Carol Rademaker

(74) Attorney, Agent, or Firm — Judy W. Chung

(57) **CLAIM**

The ornamental design for a bottle, as shown and described.

DESCRIPTION

FIG. 1 is a top, front, and right side perspective view of a bottle according to the new design;

FIG. 2 is a top, front, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the drawing views of the pour spout and threads and the bottom surface of the bottle are included for the purpose of showing environmental structure that forms no part of the claimed design.
